UNITED STATES PATENT OFFICE.

AUGUST DLOUHY, OF WALLINGFORD, CONNECTICUT, ASSIGNOR TO H. L. JUDD COMPANY, INC., OF NEW YORK, N. Y., A CORPORATION OF DELAWARE.

DESIGN FOR A CURTAIN CRANE.

Application filed May 17, 1927. Serial No. 22,009. Term of patent 3½ years.

To all whom it may concern:

Be it known that I, AUGUST DLOUHY, a citizen of the United States, and a resident of Wallingford, in the county of New Haven and State of Connecticut, have invented a new, original, and ornamental Design for Curtain Crane, of which the following is a specification.

Reference is to be had to the accompanying drawing, in which

Figure 1 is a side elevation of a curtain crane embodying my new design, and indicating by dotted lines curtain rings on the bottom bar of the crane, and

Figure 2 is a plan view thereof.

I claim:

The ornamental design for a curtain crane as shown and described.

AUGUST DLOUHY.
